UNITED STATES PATENT OFFICE.

WILLIAM F. DEISTER, OF FORT WAYNE, INDIANA, ASSIGNOR TO DEISTER MACHINE COMPANY, OF FORT WAYNE, INDIANA, A CORPORATION OF INDIANA.

HEAD-MOTION FOR CONCENTRATING-TABLES.

1,088,682.

Specification of Letters Patent.

Patented Mar. 3, 1914.

Application filed June 20, 1913. Serial No. 774,787.

To all whom it may concern:

Be it known that I, WILLIAM F. DEISTER, residing at Fort Wayne, in the county of Allen and State of Indiana, a citizen of the United States, have invented or discovered certain new and useful Improvements in Head-Motions for Concentrating-Tables, of which improvements the following is a specification.

10 The invention described herein relates to certain improvements in mechanism for imparting a vibratory motion to concentrating tables, and has for its object a construction whereby a double differential movement may be imparted to the table, and it is a further object of the invention to provide for a variation of the movements of the table in accordance with the grade of materials operated on.

20 The invention is hereinafter more fully described and claimed.

In the accompanying drawings forming a part of this specification, Figure 1 is a top plan view of a head motion for concentrating tables embodying my improvement; Fig. 2 is a sectional elevation of the same, the plane of section being indicated by the line II—II Fig. 1; Figs. 3 and 4 are detail views of certain parts illustrating their relative movements, and Fig. 5 is a sectional view illustrating a modification of the means for adjusting the relative positions of the lever; and Fig. 6 is a bottom plan view of the construction shown in Fig. 5.

30 In the practice of my invention, the power shaft 1 is provided with an eccentric of crank pin 2 on which is loosely mounted a roller 3. This roller operates in the curved seat 4 formed in the lever 5 adjacent to its free end. The pivot pin 6 supporting the opposite end of the lever, has either the portion forming the journal for the lever made eccentric to the journal portions supported by the bearings 7, or vice versa. This construction affords a convenient means for shifting the lever longitudinally as by applying a wrench to the squared projecting end of the pin and turning the latter lever is shifted relative to its operating crank pin 40 or eccentric and small or relatively large movement of the lever on its pivotal axis can be attained. The purpose of this movement will be hereinafter described.

The movement of the lever 5 is transmitted to the concentrating table by a bell crank

lever, but suitable means is interposed between the lever 5 and the bell crank lever whereby the rate of movement of the bell crank will vary at different points from the rate of movement of the lever 5. Although it is preferred to arrange the motion transmitting elements as shown in the drawings, such arrangements may be reversed. In the preferred constructions the lever 5 has attached thereto an angular block 8 preferably provided with a hardened steel wearing face, and adapted to bear against a convex portion preferably formed by a roller 9 loosely mounted on the end of one arm 10 of a bell crank lever. The other arm 11 of the lever is connected to one end of a pitman 12 adapted to be connected at its opposite end to a concentrating table. As is customary in the art, a spring is so applied to the table or some part of its operating mechanism as to exert a constant pull in the direction of the arrow x, and thereby hold the roller 9 in contact with the angular block 8. It is preferred that the connection of the pitman to the arm 11 should be adjustable so that the length of stroke imparted to the concentrating table may be varied.

The radius of curvature of the seat 4 is preferably greater than the radius of the roller 3, so that the point of bearing of the roller on the curved seat will shift back and forth according to the position of the crank. This will be clearly understood by supposing that the crank pin is in the position shown in Fig. 3, at which time the point of bearing of the roller on the seat will be in a vertical plane passing through the axes of the shaft 1 and crank pin 2. It will be observed that when the parts are in the position stated there is a relatively large space between the end a of the curved seat and the periphery of the disk measured radially of the disk. As the shaft rotates in the direction of the arrow y the roller being loose on the crank pin will roll on the curved seat shifting its point of contact thereon from b toward a. As the crank approaches arc of quickest downward movement the point of bearing of the roller on the seat will be at a. This outward shifting of the point of bearing of the roller on the seat during the quickest downward movement of the crank will modify to some extent the rate of movement of the lever. As the crank pin passes

beyond a line drawn from the center of the shaft through the point *a*, the point of contact of the roller on the seat will begin to move to the right and as the crank pin approaches the arc where its upward movement is most rapid the point of contact of the roller on the seat will be at *c* or nearer the pivotal point of the lever and hence the movement of the lever upward will be greater than its corresponding movement downward, nearly proportional to the difference between the distances of the points *a* and *c* from the pivotal point of the lever. Hence the movement of the concentrating table in one direction will increase progressively to the point of reversal, its movement in the opposite direction after reversal will be more rapid although the rate of rotation of the crank remains the same.

As the crank pin moves from the position shown in Fig. 3, the lever 5 is forced down and in its movement the arm 10 of the bell crank lever is also forced down. It will be observed that the point of bearing of the roller 9 on the block 8 is closely adjacent to the apex of the block, and hence the downward movement of the arm 10, while the apex of the block is moving into a vertical plane coincident with the axis of the shaft 1 will be slightly more rapid than that of the lever 5, until the axis of the roller 9 is also coincident with the same plane. As the apex of the block passes beyond this plane, the movement of the arm 10 will be gradually reduced at a rate approximately proportional to the shifting of the point of contact of the roller 9 away from the apex of the block.

By shifting the relative longitudinal position of the lever 5 and arm 10, which can be effected by turning the pivot pin 6, as hereinafter stated, the range of movement of the point of contact of the roller on both sides of the apex of the block can be made equal, or be made greater on the side *d* than on the side *c*. This shifting of the point of contact effects a very material change in the character of the vibrations imparted to the concentrating table. Indicator cards taken with lever 5 adjusted to different positions clearly show the difference of movements imparted to the table by reason of such adjustments.

In lieu of shifting the lever 5 longitudinally as above described, the angular block 8 may be secured to a slide 13 movably mounted on the lever, and adapted to be shifted to different positions therealong as shown in Figs. 5 and 6. In the construction shown the slide is supported by a rod 14 having a tapering portion so that by shifting the rod longitudinally the slide can be drawn tightly to its seat on the lever. The movement of the slide along the lever 5 can be effected by any suitable means, as a

bolt 15 screwing through a lug on the lever and having a swivel connection to the slide.

Attempts have been made to obtain a differential movement by means of levers bearing one on the other in such manner that the point of bearing of one lever on the other will be shifted relative to the pivotal points of levers during their operation. In this form of head motion the levers have been arranged practically parallel with their point of contact in a plane passing through pivotal axes. As the range of movement of these levers is small it follows that the change of location of their point of contact will be small and the differential due to such a change will be smaller and improperly timed. In the construction set forth the levers are arranged at an angle to each other so that a slight change in position of the levers will effect a considerable change in the positions of their point of contact relative to their pivotal points. And further the angular block 8 serves to increase the differential due to and in the same direction as is effected by the shifting of the point of contact.

I claim herein as my invention:

1. A head motion for a concentrating table having in combination a plurality of pivoted members one operative by the other means for imparting a differential movement to one of said members, means for transmitting motion from the second member to the part or element to be operated and means interposed between the said members for imparting an abnormal movement to the second member.

2. A head motion for a concentrating table having in combination a plurality of pivoted members, one operative by the other, means for oscillating one of said members means for transmitting the movement of the second member to the part or element to be operated, and means interposed between said members for imparting an abnormal movement to the second member.

3. A head motion for a concentrating table having in combination a plurality of pivoted members, one operative by the other, means for oscillating one of said members, an angular block and a curved bearing portion on the respective members, and means for transmitting the movement of the second member to the part to be operated.

4. A head motion for a concentrating table, having in combination a plurality of pivoted members, one operative by the other, means for oscillating one of said members, an angular block and a curved bearing portion on the respective members, means for adjusting the relative positions of the block and curved bearing portions, and means for transmitting the movement

of the second member to the part to be operated.

5. A head motion for a concentrating table, having in combination a plurality of pivoted members one operative by the other, means for oscillating one of said members, an angular block and a curved bearing portion on the respective members, means for shifting one of the members longitudinally, and means for transmitting the motion of the second member to the part to be operated.

6. A head motion for a concentrating table having in combination a plurality of

pivoted members, means for oscillating one of said members, an angular block on said member, a roller loosely mounted on the second member and forming a bearing for the angular block, and means for transmitting the motion of the second member to the part to be operated.

In testimony whereof, I have hereunto set my hand.

WILLIAM F. DEISTER.
